United States Patent Office.

DAVID V. B. SMART, OF TROY, NEW YORK.

Letters Patent No. 76,833, dated April 14, 1868.

IMPROVED CAR-COUPING.

The Schedule referred to in these Letters Patent and making part of the same.

TO ALL WHOM IT MAY CONCERN:

Be it known that I, DAVID V. B. SMART, of Troy, in the county of Rensselaer, and State of New York, have invented a new and improved Car-Coupling; and I do hereby declare that the following is a full, clear, and exact description thereof, which will enable those skilled in the art to make and use the same, reference being had to the accompanying drawings, forming part of this specification.

This invention relates to a new and improved method of constructing couplings for securing railroad-cars together, whereby the self-acting coupling is greatly simplified, while its effectiveness and durability are equal to any in use. And the invention consists in forming a slotted draw-head, and in connecting the coupling-pin thereto by a movable staple, as will be hereinafter described.

Figure 1 represents a side view of the draw-head partly in section, showing the position of the pin when the cars are coupled.

Figure 2 is a vertical section of fig. 1, through the line $z z$.

Similar letters of reference indicate corresponding parts.

A represents the draw-head; B is the coupling-pin; C is the movable staple to which the pin is attached; D represents the coupling-link.

The staple C passes down through the draw-head, as seen in fig. 2, its ends being turned or crooked a little, as seen, or other provision is made for preventing it from being drawn entirely out or from the draw-head.

The coupling-pin B slides and turns on this staple. Its lower end is bevelled to allow it to be readily detached from the link in uncoupling. To its upper end there is attached a short lever or knob, E, by which the pin may be operated in uncoupling.

F represents the throat of the draw-head; G is the mouth; H is the slot in the draw-head in which the coupling-pin plays.

The cars are uncoupled by raising the staple with the pin vertically, or by throwing the knob E forward, which motion will withdraw the pin from the link.

The form of the throat in the draw-head is such that the link is held in nearly a horizontal position, so that when the end of the link enters the mouth, it is conducted to the pin, which it pushes back till the pin can drop into the link, when the cars are coupled. When the link drops into the slot, and hangs on the staple by its own gravity, the car is ready for coupling without any assistance from the attendant.

In breaking up a train of cars while they are standing on the track, it is necessary to remove the pin from the link before the cars are separated. In such cases, the pin may be withdrawn entirely from the slot, and moved along on the staple and laid on the draw-head, if desired, but there is usually play enough to allow the link to be withdrawn when the pin retains its proper position for coupling.

By this simple arrangement, the cars are made self-coupling, which renders it entirely unnecessary for the attendant to go between the cars for coupling or uncoupling, as in uncoupling the pin can be operated from the platform.

Having thus described my invention, I claim as new, and desire to secure by Letters Patent—

The staple C, having its ends passing through the sides of the draw-head, in combination with the sliding coupling-pin B and the slotted draw-head, all constructed and operating as described, whereby, as the staple is raised, the pin B is swung by the knob E clear of the draw-head through the slot H, as herein shown and described.

The above specification of my invention signed by me, this 20th day of November, 1867.

DAVID V. B. SMART.
